UNITED STATES PATENT OFFICE.

THOMAS KEPPEL NORTH, OF WESTMINSTER, LONDON, ENGLAND, ASSIGNOR TO
VICKERS LIMITED, OF WESTMINSTER, ENGLAND.

SUBMARINE MINE.

1,340,288.

Specification of Letters Patent. Patented May 18, 1920.

Application filed June 21, 1917. Serial No. 176,063.

To all whom it may concern:

Be it known that I, THOMAS KEPPEL NORTH, a subject of the King of Great Britain, residing at Vickers House, Broadway, 5 Westminster, in the county of London, England, have invented certain new and useful Improvements in or Relating to Submarine Mines, of which the following is a specification.

10 This invention relates to submarine mines and has particular reference to those wherein the firing gear comprises a firing arm or member which after the launching of the mine, projects laterally from the flotation 15 chamber or mine proper, the movement of this arm relatively to the flotation chamber when the latter is struck by a ship, causing the bursting charge to be exploded. The chief object of the invention is to so construct the mine that it can be ejected from a torpedo tube; but the several features of the invention hereinafter described can be applied either individually or collectively to mines adapted to be launched or laid in the 20 usual manner.

According to the invention the aforesaid firing arm or member is hinged or jointed so that the outer portion thereof can be folded into a position to lie within the anchor and is so constructed that on the separation of the flotation chamber from the anchor it will assume and be held in its extended or lateral position relatively to the flotation chamber. The said outer portion 30 of the firing arm may be controlled by a spring preferably surrounding the inner portion of the arm and operating upon the outer portion of the arm through the intermediary of a sleeve. When the flotation 35 chamber becomes separated from the anchor during the laying of the mine and the spring has caused the outer portion of the arm to come into line with the inner portion, the said sleeve passes over the joint or hinge 40 and thereby locks the two portions together. The said sleeve may also serve through the intermediary of a suitable device to lock the firing mechanism until the sleeve has assumed its locking position.

45 In order to prevent the firing mechanism from operating to fire the mine until a predetermined time has elapsed after launch-

ing or laying the mine, a safety device is employed which, as is well understood, is held in its safety position by a plug of soluble salt or other suitable soluble substance. This plug in the present invention is contained in a casing which is so constructed and arranged that, until the flotation chamber has been submerged by its sinker or anchor, water will be prevented from gaining 55 access to the soluble plug; premature dissolution of the plug is thus avoided.

The striker head is connected to its rod or stem (which is connected to the sinker 60 or anchor cable) by one or more transverse pins or segments which are more or less pointed or rounded and engage with a circumferential groove (or with holes) formed 65 in the rod. The pins are retained in their 70 engaged position by the wall of the guide tube in which the striker head slides. This tube is formed with one or more recesses so that when the striker is being retracted by the upward lift or buoyancy of the flotation 75 chamber, after a ship has struck the mine, the outer ends of the pins will come opposite the recess or recesses whereupon the pins (owing to the formation of their inner ends and the pressure of the spring 80 on the striker head) will be moved out of engagement with the striker rod and the head will then be impelled by the striker spring against the detonator to fire the mine.

The anchor carries the paying out gear 85 for the cable and this gear comprises a fixed drum on which the anchor cable is wound; this cable passes through an arm or other suitable member connected to or forming part of a screw threaded shaft mounted in 90 the drum and carrying a nut or collar which is normally locked to the shaft and which after the arm and the shaft have been rotated to a certain extent by the unwinding of the cable from the drum, comes against 95 a fixed part and prevents further paying out of the cable. The said arm may carry a pivoted link, stirrup or other equivalent member through which the cable passes. This link or stirrup normally lies against 100 the adjacent end of the drum in which position it may be secured by a readily breakable pin or by a spring device; it is prevented from accidentally rotating (together

with the arm and the screw-threaded shaft) by a portion thereof being disposed in a groove in the drum.

In order that the said invention may be clearly understood and readily carried into effect, the same will be described more fully with reference to the accompanying drawings, in which:—

Figure 1 is a longitudinal section showing 10 a mine provided with our improvements, the parts of the mine being shown in the position they occupy prior to the launching of the mine.

Fig. 2 is a sectional inverted plan showing 15 a portion of the anchor with the anchor cable drum partly broken away to show certain parts more clearly and with the cable omitted from the drum.

Fig. 3 is an end elevation of Fig. 2 viewed 20 in the direction of the arrow in the latter figure.

Fig. 3^a is an enlarged view of part of Fig. 1.

Fig. 3^b is a section taken on line 3—3 of 25 Fig. 3^a.

Fig. 3^c is a section showing on an enlarged scale the left hand portion of Fig. 3^a in section on a plane at right angles to the plane of section of the latter figure.

Fig. 4 is an enlarged view showing the aforesaid means for preventing water from gaining access to the soluble plug.

Fig. 5 is an enlarged view of the striker, and

Figs. 6, 7 and 8 are respectively an end elevation, a side elevation and a plan viewed in the direction of the arrow of Fig. 6, showing the aforesaid nut or collar appertaining to the cable paying out gear.

In the example shown the mine comprises 40 two main elements, viz: the flotation chamber A which contains the charge chamber A' and carries the firing gear (including the aforesaid firing arm and the safety devices for preventing premature firing), and the sinker or anchor B which contains the cable B' connecting it to the flotation chamber and also contains the paying out gear for the cable. These two main elements are 45 cylindrical in shape, the flotation chamber A fitting partly within the sinker or anchor; the outer portion A² of the flotation chamber may be rounded so that the mine as a whole has somewhat the appearance of an 50 automobile torpedo, the said rounded portion constituting the nose and the sinker or anchor B the aft end.

The flotation chamber A and the anchor B are detachably connected together in any 60 suitable manner so that they will become disconnected only after the mine has left the torpedo tube or other launching device, by the pull which is exerted between the anchor and the flotation chamber as a result 65 of the weight of the former and the buoy-

ancy of the latter. In the example shown the connecting means comprise hooks a, a, a each of which has an inclined engaging surface to enable the flotation chamber to become readily disengaged from the sinker 70 or anchor as stated above. These hooks are held in position by a rope a^x until the mine is being placed in the torpedo tube. The rope is then removed and the hooks are only retained in place by the walls of the tube. 75

C is the striker head and C' is its stem; the latter is connected to a member C² to which the anchor cable B' is attached, this member carrying the inner portion D of the aforesaid firing arm. The outer portion 80 D' of this arm is hinged to the said inner portion D at d and when the parts of the mine are in the position shown by Fig. 1, the said outer portion lies more or less parallel to the longitudinal axis of the mine 85 and is disposed within the anchor. When the flotation chamber becomes detached from the anchor, the said outer portion D' of the firing arm is free to be moved by a spring d' surrounding the inner portion D, into a 90 position in line with the inner portion, whereupon the spring d' causes a collar D² to pass over the joint or hinge d and thus hold the portion D' rigidly in line with the portion D so that the firing arm projects 95 laterally from the mine; this movement of the collar is limited by a projection d^x on the said outer portion D' of the firing arm. At the same time a rod d^x connected to the collar D² is moved out of engagement with a 100 sleeve c² forming part of the member C² and with a part c³ connected to the member C² by studs c^{3x} (Fig. 3^c) between the heads of which and the member C² plugs c^{3xx} of sal-ammoniac are placed which normally 105 hold the member C² in the position shown in which a slot in the sleeve c² engages with a stud C^{3x} (Figs. 3^a and 4) on the firing gear body C³. The part c³ is formed with a gapped flange c⁰ (Fig. 3^b) coöperating with 110 an interrupted collar c⁰⁰ on a part C⁰ connected to the firing gear body C³, the said flange and collar constituting a bayonet joint connection which liberates the part c³ from the part C⁰ when relative angular movement of ninety degrees takes place between these parts. It will be observed from the 115 above description of the firing gear that the rod d^x positively holds the gear in the inoperative position until the collar D² reaches 120 its locking or retaining position. The stem C' of the striker passes through a gland and stuffing box in the body C³ of the firing gear at the base of the flotation chamber. In order to prevent sand or other foreign matter from entering the firing gear a tube c^{2x} (see Fig. 3^a) is provided inside the sleeve c² and extends from the body C³ to the outer part of the bayonet joint connection or clutch. One end of the tube is 125

130

secured to the body, the joint being made waterproof with red lead, or other suitable material; the other end of this tube is closed by the bayonet joint connection which is 5 grooved and provided with suitable packing.

Referring to Fig. 4, E is the plug of soluble salt and E' is the casing therefor attached to the firing gear seating C³. The hole through which the soluble plug E is inserted into the casing is closed by a screw threaded plug e or otherwise in a watertight manner and another hole in the casing is closed by a cylindrical projection e' or other suitable member carried by a bracket e² attached to the sleeve c²; in this manner the movement of the sleeve c² to disengage its slot from the aforesaid stud, C³, will effect relative movement between the said casing and the projection e' and result in the hole 10 being uncovered so that the sea water then has free access to the soluble plug. The casing may have an air hole e³ of such dimensions that it will not permit water to pass through it to the interior of the casing. The safety device proper comprises a piston E² whose outer surface lies in contact with the inner surface of the soluble plug E and whose rod has a chisel, beveled or otherwise suitably shaped end engaging 15 with a groove or slot c^{2xx} in the sleeve c² so that when, after the soluble plug has been dissolved, a ship strikes the mine, relative angular movement between the sleeve c² and the casing E' will be permitted to take place. Between the inner surface of the piston E² and the contiguous portion of the casing, a washer e^{2x} of rubber or other suitable material may be placed. The aforesaid screw threaded plug e in addition to closing 20 in a watertight manner the hole through which the soluble plug E is inserted into its casing E', also serves to press this soluble plug firmly against the outer surface of the piston, thus compressing the washer e^{2x} and the waterproof joint between the piston E² and the casing E'. This screw-threaded plug e may carry a rubber washer e^x which may conveniently be attached to the screw threaded plug by a thin plate e^x and a screw 25 or bolt e⁴ passing through the plate and the said plug, the washer and plug thus constituting a single unit.

In Fig. 5, C⁴, C⁴ are the aforesaid transverse pins connecting the striker head C to its stem C', and c⁴ is the circumferential groove in the stem with which pointed or rounded inner ends of these pins engage. C⁵ is the guide tube in which the striker head slides, and c⁵, c⁶ are the recesses in this 30 tube for permitting the pins to move outward as aforesaid when the striker head is sufficiently retracted, thereby liberating the striker head from its stem and permitting the striker spring to impel the head against the detonator to fire the explosive charge in

the mine; it will be seen that after the striker-head has become liberated from its stem and commences its movement under the action of the spring, the recesses c⁵, c⁶ cause the pins to move inward so that they 70 offer no impediment to the firing movement of the striker head.

F is the aforesaid fixed drum on which the anchor cable B' is wound, F' is the screw threaded shaft mounted in the drum 75 and F² is the arm connected to or forming part of the said shaft. F³ is the nut or collar normally locked to the shaft F' and serving to limit the paying out of the cable B'. The nut is capable of adjustment along 80 the shaft so that the extent to which the cable is permitted to unwind can be varied as desired. For this purpose the nut carries a spring controlled pawl or catch f which normally engages with one or the other of 85 two keyways f', f' in the shaft and which is disengaged from this keyway by the movement of a box spanner or other instrument when placed into engagement with one or more lugs F⁴ on the nut, the catch again engaging with the keyway f' when the spanner is removed after the desired adjustment 90 has been effected. The pawl or catch f is disengaged from the keyway f' by the engagement of the spanner with the underside 95 of a tail-piece f⁰ on the pawl when the spanner is being placed in position. The shank f^x of the spanner (see Fig. 2) is preferably graduated along its length so that by observing 100 these graduations against a fixed mark the adjustment of the nut is facilitated and the degree of adjustment that has been given to the nut can be readily ascertained at any time by merely inserting the spanner and reading the graduations against the fixed mark. The graduations preferably correspond to fathoms and fractions of fathoms and are marked in accordance with the diameter of the drum F and the pitch of 105 the screw threads on the shaft F'. 110

G is the aforesaid link or stirrup pivoted at g to the arm F² and provided with a guide roller g' for the anchor cable B'. This stirrup normally lies transversely against the contiguous end of the drum F' and at its 115 outer end engages with grooves f^{xx}, f^{xx}; the stirrup is retained in this position by a breakable pin g⁰ or by a spring. When the mine is launched and the anchor becomes separated from the flotation chamber, the 120 pull on the cable breaks the pin g⁰ holding the stirrup G in position against the drum and the stirrup is turned about its pivot into a position in which the roller g' is in line or approximately in line with the axis of the 125 drum, this position being determined by toe-pieces or projections g^x on the stirrup coming against parts f^{2x} of the arm F². The cable is thus effectively guided during its paying out operation. The cable drum is ar- 130

ranged with its axis coincident with that of the sinker or anchor and an annular space is left between the drum and the casting of the sinker or anchor for the accommodation of the aforesaid outer portion D' of the firing arm and a spring gear G^x (Fig. 2) carried by the portion of the cable situated between the aforesaid roller g' and a shackle C^{2x} by which the rope is connected to the member C². The cable drum is hollow and the base of the sinker or anchor is formed with an aperture through which the aforesaid spanner can be inserted for adjusting the nut F³.

15 The flotation chamber A and the anchor B may be provided with lateral fins for engaging in the guides or keyways usually provided in the torpedo tube. Of these fins those on the anchor are indicated at B^x, B^x, 20 those on the flotation chamber being carried by a portion that is not shown in Fig. 1. These fins may however be dispensed with and replaced by rings fitted near the ends of both the flotation chamber and the anchor. These rings form bearings for the mine when in the torpedo tube or other launching device.

What I claim and desire to secure by Letters Patent of the United States is:—

30 1. In a submarine mine, the combination with the anchor and the flotation chamber, of a firing arm made in two parts the outer part being normally situated within the anchor, and means whereby when the flotation chamber and the anchor become separated the said outer part of the firing arm will assume and be held in its extended or lateral position.

2. In a submarine mine, the combination with the anchor and the flotation chamber, of a firing arm made in two parts the outer part being normally situated within the anchor, and a spring controlled collar for moving said outer part into alignment with the inner part of the firing arm and for locking these parts together when the flotation chamber and the anchor becomes separated.

3. In a submarine mine, the combination with the anchor and the flotation chamber, of a firing arm made in two parts the outer part being normally situated within the anchor, a spring controlled collar for moving said outer part into alignment with the inner part of the firing arm and for locking these parts together when the flotation chamber and the anchor become separated, and means whereby the locking movement of said sleeve unlocks the firing mechanism of the mine.

4. In a submarine mine, the combination with the anchor, the flotation chamber and the firing mechanism, of a safety device comprising a plug of soluble substance contained in a casing and means connected to

the anchor cable whereby, until the flotation chamber has been submerged by its anchor, sea-water will be prevented from gaining access to the soluble plug, and means whereby the pull on the anchor cable 70 will open said casing to the sea water.

5. In a submarine mine, the combination with the anchor, the flotation chamber and the firing mechanism, of a safety device comprising a plug of soluble substance contained in a water-tight casing having a hole, a member normally closing said hole, and means whereby the pull on the anchor cable will effect relative movement between the said casing and the member and result in 80 the hole being uncovered so that the sea water then has free access to the soluble plug.

6. In a submarine mine, the combination with the striker head, its rod or stem, and 85 a spring bearing at one end against said head and at its other end against a fixed part, of a member which is carried by said head and connects the latter to the rod and means whereby when the striker head has 90 been retracted to a predetermined extent against the resistance of its spring, the member will be moved by the pressure of the said spring into the disengaged position to liberate the striker head from its rod. 95

7. In a submarine mine, the combination with the striker head, its rod or stem, and a spring bearing at one end against said head and at its other end against a fixed part, of transverse pins connecting said head to the 100 rod, the inner ends of these pins being more or less pointed to engage with a groove formed in the rod, a guide tube for normally retaining said pins in their engaged position said tube being formed with a recess so that when the striker is being retracted by the upward lift or buoyancy of the flotation chamber after a ship has struck the mine, the outer ends of the pins will come opposite the said recess whereupon the 110 pins will be disengaged from the striker rod and the head will then be impelled by its spring against the detonator to fire the mine.

8. In a submarine mine, the combination 115 with the anchor cable, of a fixed drum for said cable and a device displaced by said cable during its paying out from the drum for stopping the paying out movement when a predetermined amount of cable has been 120 paid out.

9. In a submarine mine, the combination with the anchor and its cable, of a fixed drum for the cable, an arm with which said cable co-operates, a screw threaded shaft 125 mounted in the drum and connected to said arm, a nut mounted on said shaft, and means for normally locking said nut to the shaft.

10. In a submarine mine, the combination with the anchor and its cable, of a fixed an- 130

- chor-cable drum, a screw threaded shaft engaging with said drum and rotated by the paying out of the anchor cable, a nut mounted on said shaft, and a pawl or catch carried by said nut and normally engaging with a longitudinal groove or keyway in the shaft, said pawl being so constructed that the placing of a spanner or other actuating instrument into engagement with the nut 10 will disengage the pawl.
11. In a submarine mine, the combination with the anchor and its cable, of a fixed anchor-cable drum, a screw threaded shaft engaging with said drum and connected to an 15 arm which carries a pivoted member through which the cable passes, the said

member being adapted to assume a position such that its outer end will come in line or approximately in line with the axis of the drum.

12. In a submarine mine, the combination with the anchor and its cable, of a fixed anchor-cable drum, a screw threaded shaft connected to an arm which carries a pivoted member through which the cable passes, this member normally lying against the adjacent end of the drum and being temporarily retained in this position.

In testimony whereof I affix my signature. 30

THOMAS KEPPEL NORTH.
